COMBINED PUMP AND INLET SCREEN

Lee W. Davis, Oklahoma City, Okla., assignor to Little
Giant Corporation, Oklahoma City, Okla.

Filed Sept. 10, 1969, Ser. No. 19,097

Term of patent 14 years

Int. Cl. D15—02

U.S. Cl. D65—1

FIG. 1 is a top plan view of a combined pump and inlet screen showing my design;

FIG. 2 is a side elevational view thereof;

FIG. 3 is a bottom plan view thereof;

FIG. 4 is a front elevational view thereof with the inlet screen removed;

FIG. 5 is a bottom plan view of FIG. 4; and

FIG. 6 is a perspective view of the inlet screen.

I claim:

The ornamental design for a combined pump and inlet screen, as shown.
